The ornamental design for an animal waterer, as shown and described.

DESCRIPTION

FIG. 1 is a perspective view of an animal waterer showing my new design;

FIG. 2 is a side elevation view of the embodiment shown in FIG. 1;

FIG. 3 is the other side elevation view of the embodiment shown in FIG. 1;

FIG. 4 is a rear elevation view of the embodiment shown in FIG. 1;

FIG. 5 is a front elevation view of the embodiment shown in FIG. 1;

FIG. 6 is a top plan view of the embodiment shown in FIG. 1;

FIG. 7 is a bottom plan view of the embodiment shown in FIG. 1; and,

FIG. 8 is a top plan view of a second embodiment of FIG. 1, the difference being in the addition of a second bowl.

The broken lines are for purposes of illustration only and form no part of the claimed design.
